UNITED STATES PATENT OFFICE.

JOHN M. HARGRAVE, OF CINCINNATI, OHIO.

DESIGN FOR A TOOL-HANDLE.

51,641.

Specification for Design.

Patented Jan. 1, 1918.

Application filed October 9, 1916. Serial No. 124,737. Term of patent 14 years.

To all whom it may concern:

Be it known that I, JOHN M. HARGRAVE, a citizen of the United States, residing at Cincinnati, in the county of Hamilton and State of Ohio, have invented a new, original, and ornamental Design for Tool-Handles, of which the following is a specification, reference being made to the accompanying drawing, forming part thereof.

The figure is a side elevation of my new design of handle for tools as applied to a screw driver.

The design consists in the general outline of the handle and principally in the outline of the hand hold portion 1, and its relation to the body or shank portion 2, in projecting at right angles to said body portion. The upper surface of the hand hold por-

tion longitudinally is representative of an ogee configuration developing into a beading at each end.

Having thus described my invention, I claim:—

The ornamental design for tool handle consisting of a hand hold portion at right angles to the body portion and the hand hold portion substantially as shown and described.

Signed in the city of Cincinnati, county of Hamilton, State of Ohio, this 6th day of October, 1916.

JOHN M. HARGRAVE.

In the presence of—

EMMA SPENER,
L. A. BECK.
